(57) **CLAIM**

The ornamental design for a raspitory, as shown and described.

DESCRIPTION

FIG. 1 is a front perspective view of a raspitory according to the present invention.

FIG. 2 is a left side view of the raspitory of FIG. 1.

FIG. 3 is a right side view of the raspitory of FIG. 1.

FIG. 4 is a top view of the raspitory of FIG. 1.

FIG. 5 is a bottom view of the raspitory of FIG. 1.

FIG. 6 is a front view of the raspitory of FIG. 1; and,

FIG. 7 is a rear view of the raspitory of FIG. 1.

The broken lines shown in FIGS. 1-7 illustrate portions of the raspitory that form no part of the claimed design. The broken lines shown between the handle in FIGS. 1-5 illustrate a break in length and forms no part of the claimed design.
